(57) **CLAIM**

The ornamental design for a lavalier microphone, as shown and described.

DESCRIPTION

FIG. 1 is a front perspective view of a lavalier microphone showing our design.

FIG. 2 is a bottom rear perspective view of the lavalier microphone.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of a portion of the lavalier microphone labeled 9 in FIG. 1.

FIG. 10 is an enlarged view of a portion of the lavalier microphone labeled 10 in FIG. 1; and,

FIG. 11 is a front perspective reference view of the lavalier microphone showing the lavalier microphone in another state.

The broken lines in the drawings show portions of the lavalier microphone that form no part of the claimed design. The broken lines showing a sponge and clip in FIG. 11 depict environment and form no part of the claimed design. The dot-dash lines in FIGS. 9 and 10 shows the boundary of the enlarged view and forms no part of the claimed design.

1 Claim, 11 Drawing Sheets
